(57) **CLAIM**

The ornamental design for a roof rack crossbar end fitting, as shown and described.

DESCRIPTION

FIG. 1 is a perspective view of a roof rack crossbar end fitting showing my new design;

FIG. 2 is a front elevation view thereof;

FIG. 3 is an exploded perspective view thereof;

FIG. 4 is a left side elevation view thereof;

FIG. 5 is a rear elevation view thereof;

FIG. 6 is a right side elevation view thereof;

FIG. 7 is a plan view thereof; and,

FIG. 8 is a underside view thereof.

In the drawings, the broken lines depict portions of the roof rack crossbar fitting that form no part of the claim.
